UNITED STATES PATENT OFFICE.

ALBERT VAN WAGENEN, OF BOSTON, MASSACHUSETTS.

SOLE-FASTENER.

SPECIFICATION forming part of Letters Patent No. 331,926, dated December 8, 1885.

Application filed April 3, 1885. Serial No. 161,139. (No model.)

To all whom it may concern:

Be it known that I, ALBERT VAN WAGENEN, of Boston, county of Suffolk, State of Massachusetts, have invented an Improvement 5 in Sole-Fasteners, of which the following description, in connection with the accompanying drawings, is a specification, like letters on the drawings representing like parts.

The object of my invention is the production of a novel sole-fastener.

My improved sole-fastener is composed of a strip or ribbon of sheet metal corrugated or indented and folded about a wire core, the projections or corrugations of the strip engaging 15 the leather or other material into which the fastener is driven.

Figure 1 represents on an enlarged scale an indented strip or ribbon of sheet metal with central wire core therein, part of the strip being shown as infolded within the strip to make 20 sole-fastening material in accordance with my invention; Fig. 2, a cross-section of Fig. 1 in the dotted line $x-x$. Fig. 3 shows a sole-fastener detached, and Figs. 4 and 5 modified forms of strips.

A thin metal strip or ribbon, A, indented or corrugated in any desired manner, so as to present projections or an uneven surface at its outer side, has a wire, B, laid against it, 30 and the strip or ribbon by the action of a suitable die, and by methods well known to those conversant with metal-working, the said strip or ribbon is bent closely about the said wire core, as shown at the left of Fig. 1 in the section Fig. 2. As the sole-fastening material is severed, the cutter used will sever the material in usual manner, so as to leave a point, 35 as at the left of Figs. 1 and 3. The projections at the outside of the fastener engage the leather and act to retain the fastener in place.

The fastening material made as described may be cut into lengths suitable for fasteners in a nailing-machine for boot and shoe work, or be cut and made into nails to be fed into a 40 machine separately.

In another application, Serial No. 161,138, filed concurrently herewith, I have shown and claimed a sole fastener composed of a corrugated or indented strip bent to form a cylindrical body.

If desired, the cylindrical body representing the wire-like material to be cut into short lengths for the production of fasteners may be subjected to a galvanizing process, to fill any spaces left as the result of bringing the 55 strip of sheet-iron into cylindrical form.

I am aware that nails for sole-fastenings are commonly indented or serrated. I am also aware that shoe-sole fastenings have been made of smooth or plain strips of metal folded 60 about a fibrous core, and also that a tubular or tube-like fastener with open center and side has also been used, the fastening separating as it is driven into the leather.

In accordance with my invention, the strip 65 from which the fastener is made is first corrugated or indented, and being done before the metal is put into nail shape, the cost of manufacture is decreased, and there is actually no waste of stock, and the indentations, added to 70 the sheet-metal nail, make that class of nail or fastener operative and valuable. The addition of the metallic core greatly stiffens the fastener, and the indentations of the strip act in a measure to aid in holding the core in 75 place.

I claim—

The herein-described sole-fastening material, composed of a wire core enveloped by an indented or corrugated metallic strip, all 80 substantially as described.

In testimony whereof I have signed my name to this specification in the presence of two subscribing witnesses.

ALBERT VAN WAGENEN.
